[57] **CLAIM**

The ornamental design for a mobile telephone unit, as shown and described.

DESCRIPTION

FIG. 1 is a top plan view of a mobile telephone unit, showing our new design;

FIG. 2 is a front elevational view thereof;

FIG. 3 is a bottom plan view thereof;

FIG. 4 is a rear elevational view thereof;

FIG. 5 is a right side elevational view thereof;

FIG. 6 is a left side elevational view thereof;

FIG. 7 is a left side, top and front perspective view thereof; and

FIG. 8 is a similar perspective view thereof with the handset spaced apart from the stand.

The coiled cord is shown fragmentarily in some views for ease of illustration.
